UNITED STATES PATENT OFFICE.

EDWARD E. SANDS, OF HOUSTON, TEXAS.

APPARATUS FOR BUILDING CONCRETE STRUCTURES.

Application filed August 23, 1920. Serial No. 405,353.

To all whom it may concern:

Be it known that I, EDWARD E. SANDS, a citizen of the United States, residing at Houston, in the county of Harris and State 5 of Texas, have invented certain new and useful Improvement in an Apparatus for Building Concrete Structures, of which the following is a specification.

This invention relates to new and useful 10 improvements in an apparatus for building concrete structures and includes also the method or process of erection.

In erecting concrete buildings in accordance with the ordinary method, forms are erected, usually from lumber into which the 15 columns are poured, and beam and slab forms are also constructed for the formation of the beams and floor and roof slabs, and these beam and slab forms are supported by 20 a large number of timber columns. All of these forms and timber columns are torn away when the concrete has set, and the lumber used in practically ruined, causing a great wastage of lumber. The herein de- 25 scribed apparatus and method of its use makes it possible to erect the ordinary form of reinforced concrete structure without the destruction of or damage to any of the lumber or forms used in the process of erection.

With the above and other objects in view 30 the invention has particular relation to certain novel features of construction and method of use, an example of which is given in this specification and illustrated in the ac- 35 companying drawings, wherein:—

Figure 1 shows a sectional view of a floor or roof slab showing two supporting columns and illustrating the apparatus em- 40 ployed in removing the forms.

Figure 2 shows a fragmentary side view of said apparatus, and

Figure 3 shows a side view of the foot- 45 ing, showing the column mounted thereon.

Referring now more particularly to the drawings wherein like numerals of reference 50 designate similar parts in each of the figures, the numeral 1 refers to the footing, and the numerals 2 and 3 designate columns which are mounted on said footings, it being un- 55 derstood that a great number of footings and columns will be employed, depending upon the character of the structure. When this footing is formed the lower end of a rod 4 is secured therein around which the con- crete hardens, and this rod projects up above 60 the footing. The lower ends of the columns

have the bores 5 whose upper ends are turned outwardly through the side of the column. The upper end of the rod 4 projects up into this bore 5 and after the 60 column is in place the bore may be filled with concrete in plastic state from the side opening thereof. An inverted U-shaped rod 6 is cast in the upper end of the column forming a convenient means for engage- 65 ment by a hook or other apparatus to be used in lifting the column into place, in the event the column is pre-cast before erection. Each column is also provided with one or more comparatively large openings 70 7, the number of openings employed depend- ing on the number of stories in the building.

It is to be here observed that if desired, the columns may be built in place or they may be pre-cast, the latter method being 75 ordinarily the more economical.

When the columns are built by the method just described, or built in place, the roof slab or floor slab 8 is then constructed in a manner presently to be described:— 80

The corresponding openings 7 are ar- ranged in alignment and a short beam 9 is inserted through each of said openings. This beam is long enough to project out on each side of the column, thus forming a support 85 for the forms by means of which the slab is molded. On the top of the respective ends of each beam 9 are the supporting blocks, formed of reversely tapered wedge-shaped sections 10, 10 and 11, 11. These sections are 90 held in position by means of the pins 12, 12 which are driven through the sections 10, adjacent the outer edges of the sections 11, and into the beam 9 underneath. Channel irons 13, 13 are mounted on these support- 95 ing blocks and the channel irons are clamped against the columns by means of the usual bolt and drift pin 14. Outside columns will require only one channel iron, which is clamped to the inner side thereof by said 100 bolt, but interior columns will require a channel iron on each side. These channel irons form supporting beams for the joists 105 15 which may be of wood or metal. A smooth floor 16 is supported by the joists 15 which may also be formed of wood or metal.

It is customary to use one or more arches or domes in the construction of slabs of this character, although in some cases none will 110 be used. In the form shown the domes are indicated by the numerals 17 and are arch-

like forms which are supported on the floor 16. The plastic material is then poured on said floor and covers said domes and the upper surface thereof is brought to a smooth 5 finish, and formed integrally therewith are suitable beams and girders. After the concrete is set the floor will then be removed by means of an apparatus described hereinafter.

10 Near each corner of each slab there is left an opening 18, and extending downwardly through these openings and through the floor are the lifting screws 19 whose upper ends are outwardly threaded and whose 15 lower ends are clasped to the clevises 20. A lifting beam 21 is inserted through aligned clevises under the supporting beams 13. Threaded upon the upper end of the lifting screws 19 are the hand wheels 22, and underneath them are bearing plates 23 which rest upon the slab, and interposed between them are anti-friction bearings 24. Four of these lifting screws or jacks are used for each panel or slab. By the use of said jacks 25 the beam 21 may be brought up closely against the supporting beams 13, and the pins 12, the sectional blocks 10 and 11, the beam 9, and the bolt 14 are then removed, as shown in connection with the column 2 30 at the left hand side of Figure 1.

By the aid of the four jacks the supporting beams 13 are then lowered, and as they are lowered they will carry downwardly with them the joists 15, the floor 16 and the 35 domes 17, to the ground or to the floor below. None of these parts will be injured by the operation described and may be used again.

It is obvious that by the apparatus and method herein described the use of temporary columns or struts are eliminated and 40 the forms for the floor or roof slabs are supported from the columns of the building while said slabs are being cast, and when these forms are removed said columns will support the slabs formed. 45

What I claim is:—

1. A device of the character described consisting of supporting beams inserted through the supporting columns of a building, a wedge-shaped supporting block on 50 each end of said beam, supporting beams mounted on said blocks and forms for molding concretes material supported by said last mentioned beams.

2. In a concrete structure, supporting 55 columns, each having a transverse opening therethrough, a beam inserted into each opening and projecting each way beyond the column and provided to support the forms used in the construction of said buildings. 60

3. In a concrete structure, supporting columns, each having a transverse opening therethrough, a beam inserted into each opening and projecting beyond the column and provided to support the forms used in 65 the construction of said building.

In testimony whereof I have signed my name to this specification in the presence of two subscribing witnesses.

EDWARD E. SANDS.
